GLOVE

Herman A. Gillian, Kewanee, Ill., assignor to
The Boss Manufacturing Company, Kewanee,
Ill., a corporation of Illinois

Application July 25, 1938, Serial No. 231,241

10 Claims.

(Cl. 2—159)

This invention relates to improvements in gloves and more particularly has to do with improved seam protecting and reinforcing means therefor.

5 Objects of the invention are to provide an improved seam cover for gloves that will afford good protection for the same against wear and strain, that will not interfere with the handling of work, and that can be easily incorporated with standard 10 forms of gloves in the manufacture thereof without effecting the sewing in of other parts of the glove.

A particularly important novel characteristic of the invention resides in the special form of 15 seam cover and its connection with the glove structure so that while the seam cover is unfastened at its outer edge, the same is maintained in position to shield the seam and so as not to interfere with the handling of work.

20 Another important novel feature of the invention lies in the special form of the seam cover provided with a welt strip portion forming a continuation of a marginal edge portion of the seam and interposed with said edge portion in the glove 25 seam.

The invention, with other objects, novel features and advantages thereof, and the particular construction, combination and arrangement of parts comprising the same, will be understood 30 from the hereinafter contained detailed description, when considered in connection with the accompanying drawings forming part hereof and illustrating several embodiments of the invention.

In the drawings:

35 Figure 1 is a plan view of the front of a glove provided with seam protecting and reinforcing means in accordance with the present invention.

Fig. 2 is a similar view of the back of the glove.

40 Fig. 3 is a plan view of the pattern or blank for the front of the glove.

Fig. 4 is a view of the blank for the combined seam cover and welt.

Fig. 5 is a plan view of the front of the glove folded back upon itself and the inner thumb part 45 folded back, with the seam cover and welt laid thereon and showing the outer line of stitching that connects the seam cover to the palm section and inner thumb part.

Fig. 6 is a plan view of the parts shown in Figure 5 with the outer thumb part superimposed thereon and partly sewed in.

Fig. 7 is a view of the blank for the outer thumb part.

Fig. 8 is a plan view of the parts shown in Figure 6 inverted and after the outer thumb part

has been completely sewed in, the parts being shown inside out.

Fig. 9 is a view of the blank for the cover for the seam that connects the fronts of the second and third fingers to the palm section.

Fig. 10 is a fragmentary plan view showing the seam cover blank, illustrated in Figure 9, laid inside out upon and stitched to the upper portion of the palm section and adjoining marginal portions of the finger sections of the blank illustrated in Figure 3.

Fig. 11 is a fragmentary plan view showing the finger fronts of the second and third fingers folded down and stitched to the palm section over the seam cover.

Fig. 12 is a plan view of the parts shown in Figure 11 inverted, with the finger fronts extending upwardly.

Fig. 13 is a plan of the blank for the fronts of the second and third fingers.

Fig. 14 is a transverse section on the line 14—14 of Figure 1.

Fig. 15 is a transverse section on the line 15—15 of Figure 1.

Fig. 16 is a section through the seam cover and adjoining parts on the line 16—16 of Figure 1.

Fig. 17 is a fragmentary plan view of the front of the glove with the gauntlet broken away to show the lower end portion of the seam cover for the thumb seam disposed at the inner side of 30 the gauntlet.

Fig. 18 is a plan view of the front of a glove provided with a modified form of seam cover.

Fig. 19 is a transverse section on the line 19—19 of Figure 18.

Fig. 20 is a view of the blank for the seam cover shown in Figure 18.

Fig. 21 is a fragmentary plan view of the front of a glove provided with a seam cover on each side of the thumb, the latter being formed partly 40 of leather and partly of cloth.

Fig. 22 is a fragmentary view of the construction illustrated in Figure 21, showing the other side of the thumb.

Fig. 23 is a transverse section on the line 23—23 of Figure 21.

Fig. 24 is a fragmentary plan of the front of a glove having a semi-round, part leather and part cloth thumb, and provided with a modified form 50 of seam cover.

Fig. 25 is a view similar to Figure 24 with the thumb turned back.

Fig. 26 is a transverse section on the line 26—26 of Figure 24.

Fig. 27 is a view of the blank for the seam cover shown in Figures 24, 25 and 26.

While several preferred embodiments of the invention are illustrated in the drawings, it will be understood that minor changes and modifications may be made in the particular constructions shown, and the invention may be embodied in other forms as will appeal to those skilled in the art and falling within the scope of the appended 10 claims, without departing from the spirit of the invention.

The invention is applicable to various types of gloves constructed of many different kinds and combinations of materials, including all 15 leather and all fabric gloves, and gloves made partly of leather and partly of fabric. In the particular embodiments of the invention illustrated, by way of example in Figures 1 to 20 of the drawings, the invention is shown applied to a 20 well known form of workmen's glove, the same comprising the front blank 1, illustrated in Figure 3 of the drawings, including a palm section 2, inner thumb part 3, and finger sections 4, 5, which form the fronts and sides of the first and 25 fourth fingers. The back or outer thumb part is formed by a blank 6. In forming the glove, the inner thumb part 3 is folded back, and the outer thumb part 6 is connected with the inner thumb part and the palm section 2 by a seam 7. A piece 30 8, shown in Figure 13, forms the fronts of the second and third fingers, said piece being folded along the slit 9 therein, and the edge portions 10, 11 being connected with the edge portion 12 of the palm section by a seam 13. In the particular 35 construction shown, the blank 1 and the other parts referred to are all constructed of leather. The glove has a full cloth back 13' and a wrist portion or gauntlet 14 connected to the palm section and back by a seam 15.

40 In accordance with the present invention, the glove is provided with a combined seam cover and welt 16, 17, for part of the seam 7, which connects the outer thumb part 6 with the inner thumb part 3 and the palm section. As shown, 45 the seam cover 16 extends from a portion of the seam connecting the inner and outer thumb sections down to the wrist portion or gauntlet 14, and the welt 17 extends from the upper end of the seam cover well around the end of the thumb. 50 The seam cover and welt in the form of a unit are constructed from a continuous piece or blank of leather or other suitable material, the blank having the main seam cover part 16 and the narrow welt strip portion 17 extending from the 55 upper end thereof. The seam cover part 16 of elongated form decreases in width towards its ends and has a substantially straight outer marginal edge portion b—c, and an outwardly curved inner marginal edge portion d—e, the latter being 60 of greater length than the opposite marginal edge portion b—c. As shown in Figure 4 of the drawings, the blank is cutout to form the curved edge 19 between adjoining straight edges of the seam cover part and the welt portion, the latter being 65 where it joins the seam cover part being curved and forming a continuation of the outwardly curved marginal edge portion d—e, of the seam cover. The blank is scolloped at 20. This and the curved cutout at 19 allows the welt portion 70 to conform to the line of curvature of that part of the seam 7 which connects the outer and inner thumb parts. The seam cover part 16 at its lower end is cutout along the lines f and g, to 75 provide the end portion 21 extending to one side

of and longitudinally beyond the outwardly curved marginal edge portion d—e.

In making up the glove, the seam cover part 16 is first secured wrong side out along its longer outwardly curved marginal edge portion d—e to the palm section 2 and the inner thumb part 3 by stitching 22 outwardly of the seam 7, as shown in Figures 5 and 8. The outer thumb part 6 is next sewed in, the outwardly curved marginal edge portion of the seam cover and its welt extension being caught in the seam 7 between the other parts as shown in Figure 8, the thumb being shown inside out in this view. When the thumb is turned right side out, the lower end portion 21 of the seam cover part 16 is disposed at the inner side of the wrist portion or gauntlet and secured thereto by the stitching 15. The seaming of the cover wrong side out along its convex inner marginal edge portion d—e to the concave or 15 reversely curved marginal portion of the palm section and the inner thumb part outwardly of the seam 7, forces the main outer portion of the cover right side out back over the seam 7, and maintains the same in a position extending alongside the outer thumb part, as shown in Figure 1, 20 to shield the seam 7 and also so that the seam cover will not interfere with the handling of work. 25

The glove is also provided with a seam cover for the seam 13 that connects the edge portions 10, 11 of the fronts of the second and third fingers with the edge portion 12 of the palm section. This seam cover, see Figure 9, is formed by an elongated piece 23 that decreases in width towards its ends, the same having a substantially straight outer marginal edge portion h—k and an 30 outwardly curved inner marginal portion l—m. The seam cover is secured inside out along its longer outwardly curved marginal edge portion to the palm section 2 and adjoining marginal portions of the finger sections 4 and 5 by stitching 35 24 outwardly of the seam 13, as shown in Figure 10, and the curved marginal edge portion is caught in the seam 13 when the fronts of the second and third fingers are sewed in. As will be understood, in Figure 10 the finger sections 4 and 45 5 are shown folded down in front of the palm section to fully expose the stitching 24.

As in the seam cover construction for the thumb hereinbefore described, the seaming of the longer outwardly curved marginal portion l—m 50 wrong side out to the palm section and the adjoining marginal portions of the finger sections 4 and 5 outwardly of the seam 13 as illustrated in Figure 10, forces the main outer portion of the seam cover right side out back over the seam 13. 55 When the finger sections 4 and 5 are folded back to normal position from the position shown in Figure 10 after the stitching of the seam cover and the fronts of the second and third fingers to the palm section, the main outer portion of the seam cover is maintained in the position shown in Figure 16 extending over the seam 13 alongside the fronts of the second and third fingers to protect the seam and not interfere with the handling of work. 60

65 The invention contemplates making the seam covers for the thumb of different lengths to meet different requirements as the wear and strain on the thumb seam may occur at different points along the same depending upon the nature of the 70 work performed. The modified form of seam cover for the thumb illustrated in Figures 18, 19 and 20, is substantially the same as that hereinbefore described and illustrated in Figures 1 to 8 of the drawings, except that this modified con- 75

struction is shorter and does not have the welt strip extension. In Figures 18, 19 and 20, the glove is shown without the seam cover for the seam 25 that connects the fronts of the second and third fingers to the palm section. In these views, 26 designates the palm section, 27 the inner thumb part, 28 the outer thumb part, and 29 the seam, which connects the outer thumb part to the palm section and the inner thumb part. The seam cover 30 is formed from an elongated piece, illustrated in Figure 20, said piece decreasing in width towards its ends and having an outwardly curved inner marginal edge portion o-p of greater length than the opposite outer marginal edge q-r. The seam cover is secured wrong side out along its longer marginal edge portion o-p to the palm section 26 by stitching 31 outwardly of the seam 29, and the inner marginal edge portion o-p is interposed in the seam 29, the main outer portion of the seam cover being disposed right side out over its seam 29 and the seam 29 alongside the outer and inner thumb parts.

It will be understood, that the invention is applicable to gloves having all leather and all fabric thumbs, and thumbs formed partly of leather and partly of fabric, and to continuous, semi-round, and other forms of thumbs. The invention contemplates providing a seam cover on either or both sides of the thumb, for example as shown in Figures 21, 22 and 23 of the drawings. The construction of glove shown in these views is the same as that illustrated in Figures 1 to 20, except that the thumb is part leather and part cloth. In Figures 21, 22 and 23, 32 designates the palm section and 33 the inner thumb part formed of leather. The outer thumb part is formed of a piece 34 of leather and a piece 35 of cloth. 36 designates the seam that connects the thumb to the palm section 32 and the portion 36' of the back of the glove. 37 and 38 designate seam covers at opposite sides of the thumb. These seam covers are of the same construction as that hereinbefore described and illustrated in Figures 18, 19 and 20, this form of seam cover being interchangeable or adapted to be applied on either side of the thumb. 39 designates the line of stitching connecting the seam cover 31 to the palm section 32 outwardly of the seam 36. The seam cover 38 at the other side of the thumb is connected to the back portion 36' outwardly of the seam 36 by stitching 41. As shown, the main outer portions of the seam covers 37 and 38 are disposed right side out over their respective seams 39 and 41, and over the seam 36 alongside the thumb. The seam cover 38 is shown with its outer marginal edge portion fastened down by stitching 42, and when particularly desired, the outer marginal edge portion of the seam cover in any of the constructions illustrated in the drawings, may be similarly fastened down.

In Figures 24, 25, 26 and 27 is shown a glove having a semi-round, part leather and part cloth thumb provided with a seam cover. In the construction here shown, 43 designates the palm section, 44 a thumb part of leather, and 45 a thumb part of cloth. 46 is the seam connecting the thumb to the palm section 43. The seam cover designated 47, is constructed similarly to the seam cover illustrated in Figures 18, 19 and 20, the same being formed from an elongated piece, shown in Figure 27, said piece decreasing in width towards its ends and having an outwardly curved inner marginal edge portion s-t of greater length than its opposite outer marginal edge u-v.

In this particular instance, the seam cover blank differs slightly in shape from the seam cover blank shown in Figure 20, the same tapering more sharply near one end than at the other. The seam cover 47 is secured wrongside out along its longer inner marginal edge portion s-t to the palm section 43 by stitching 48 outwardly of the seam 46, and the inner marginal edge portion s-t is interposed in the seam 46, the main outer portion of the seam cover being disposed right side out over its seam 48 and the seam 46, and forms a crease coincident with the crotch of the thumb.

It will be noted that the invention provides a seam cover that will afford good protection for the seam, the same reinforcing and strengthening as well as shielding the seam from wear. The seam that connects the seam cover to the palm section and inner thumb part to one side of the thumb seam stands out therefrom, the construction furnishing double protection for the thumb seam in the region subject to greatest wear and doubling the wearing qualities of the glove.

The particular construction and connection of the seam cover to the glove is such that the seam cover is maintained in a position so that it will not interfere with the handling of work; it can be made in different lengths and applied at different points along the seam to meet the requirements in different classes of work, and it can be easily introduced into standard types of gloves in the manufacture of the same without interfering with the sewing in of other parts of the glove. As will be appreciated, the combined seam cover and welt provides a welt in conjunction with the cover, and the same in the form of a unit can be easily introduced into the glove structure.

What I claim is:

1. A glove having portions united by a seam, a seam cover for a part of said seam formed of an elongated piece having a convex inner marginal edge portion, said cover being stitched wrong side out along its convex inner marginal portion to a concave marginal portion of a portion of the glove outwardly of said seam, the main portion of the cover extending right side out back over a part of the first mentioned seam.

2. A glove having portions united by a seam, a seam cover for a part of said seam formed of an elongated piece having a convex inner marginal edge portion, said cover being stitched wrong side out along its convex inner marginal portion to a concave marginal portion of a portion of the glove outwardly of the first mentioned seam, and said convex marginal portion being also interposed in said first mentioned seam, the main portion of the cover extending right side out back over a part of the first mentioned seam.

3. A glove having a seam that connects an outer thumb part to an inner thumb part and to the palm section, and a cover for said seam formed of an elongated piece having a convex inner marginal edge portion, said cover being stitched wrong side out along its convex inner marginal portion to a concave marginal portion of the palm section and the inner thumb part outwardly of said first mentioned seam, the main portion of said cover extending right side out back over a part of said first mentioned seam.

4. A glove having portions united by a seam, a seam cover for a part of said seam formed of an elongated piece having a convex inner marginal edge portion, said cover being stitched wrong side out along its convex inner marginal portion to a

- concave marginal portion of a portion of the glove outwardly of said first mentioned seam, the main portion of said cover extending right side out back over a part of the first mentioned seam, and said cover having a welt strip portion extending from one end thereof, said welt strip portion forming a continuation of said convex inner marginal edge portion of the cover and being interposed in said first mentioned seam.
5. A glove having a seam that connects an outer thumb part to an inner thumb part and to the palm section, and a cover for said seam formed of an elongated piece having a convex inner marginal edge portion, said cover being stitched wrong side out along its convex inner marginal portion to a concave marginal portion of the palm section and the inner thumb part outwardly of said first mentioned seam, the main portion of said cover extending right side out back over its seam and a part of the first mentioned seam, and said cover having a welt strip portion extending from the upper end thereof, said welt strip portion forming a continuation of the convex inner marginal edge portion of the cover and being interposed in said first mentioned seam.
10. A glove having a seam that connects an outer thumb part of the palm section, and a cover for said seam formed of an elongated piece having a convex inner marginal edge portion, said cover being stitched wrong side out along its convex inner marginal portion to a concave marginal portion of the palm section outwardly of the first mentioned seam, the main portion of the cover extending right side out back over a part of the first mentioned seam, and said seam cover extending to the wrist portion of the glove and having a lower end portion located to one side of its convex inner edge portion and extending longitudinally therebeyond, said end portion being secured to the wrist portion and being secured thereto.
15. A glove having a seam that connects a finger portion with an adjoining section, and a cover for a part of said seam formed of an elongated piece having a convex inner marginal edge portion, said cover being stitched wrong side out

along its convex inner marginal portion to a concave marginal portion of said adjoining section outwardly of the first mentioned seam, the main outer portion of the cover extending right side out back over a part of the first mentioned seam, and the outer marginal edge portion of said cover being stitched to said finger portion.

8. A glove having a seam that connects a thumb part to the palm section, said seam extending transversely along the crotch of the thumb, and a cover for said seam formed of an elongated piece having a convex inner marginal edge portion, said cover being stitched wrong side out along its convex inner marginal portion to a concave marginal portion of the palm section outwardly of the first mentioned seam so that the main outer portion of said cover extends right side out back over the first mentioned seam, and forms a crease coincident with the crotch of the thumb.

9. A glove having a seam connecting second and third finger front sections to the palm section, and a cover for said seam formed of an elongated piece having a convex inner marginal edge portion, said cover being stitched wrong side out along its convex inner marginal portion to the marginal portion of the palm section and to the first and fourth fingers upwardly and around the second and third finger front sections outwardly of the first mentioned seam, said stitching at the palm and finger sections constituting in effect a concave line of stitching whereby the main outer portion of the cover will extend right side out back over a part of the first mentioned seam.

10. A glove having portions united by a seam, and means for protecting said seam comprising a cover piece therefor of elongated and flexible form having a convex inner marginal edge, the adjoining portion of the glove having an edge of a conformation differing from said convex inner marginal edge, and stitching for securing said edge portions together outwardly of the seam to be protected, said stitching and non-conforming edges secured thereby being adapted to cause the cover when extended right side out and under tension to overlie the seam.

HERMAN A. GILLIAN.

CERTIFICATE OF CORRECTION.

Patent No. 2,210,484.

August 6, 1940.

HERMAN A. GILLIAN.

It is hereby certified that error appears in the printed specification of the above numbered patent requiring correction as follows: Page 1, first column, line 23, for the word "seam" read --same--; and second column, line 17, after "fronts" insert --of the second and third fingers--; page 4, first column, line 28, claim 6, for "of" read --to--; lines 41 and 42, same claim, strike out "and being secured thereto"; and that the said Letters Patent should be read with this correction therein that the same may conform to the record of the case in the Patent Office.

Signed and sealed this 17th day of September, A. D. 1940.
